C. R. MARTINEAU

SHIRT SLEEVE SUPPORTER

Filed Sept. 17, 1925

Fig. 1.

Inventor:

Clarence R. Martineau

By

Frank C. Currie
Attorney

UNITED STATES PATENT OFFICE.

CLARENCE R. MARTINEAU, OF ALBANY, NEW YORK.

SHIRT-SLEEVE SUPPORTER.

Application filed September 17, 1925. Serial No. 56,847.

Reference may be had to the accompanying drawings, and the reference characters marked thereon, which form a part of this specification. Similar characters refer to 5 similar parts in the several figures therein.

The principal object of the invention is to provide a sleeved garment with means whereby the sleeves can be shortened if desired.

10 Other objects will appear in connection with the following description.

Fig. 1 of the drawings is a front view of an outer shirt showing the sleeves provided with different forms of shirring mechanism 15 embodying my invention.

Fig. 2 is a vertical section taken through the shirring mechanism on the broken line 2—2 in Fig. 1.

Fig. 2^a, is a similar section showing a 20 modification of the shirring mechanism shown in Fig. 2.

Fig. 2^b, is a front view of a broken-away portion of a shirt sleeve further illustrating the construction shown in Fig. 2^a.

25 Referring to the drawings, in Fig. 1, I have shown on the right-hand sleeve, 1, of a shirt, 2, shirring mechanism consisting of a cord, 3, attached at its upper end, permanently or frictionally, to the garment as 30 by means of an eyelet, 4, in the sleeve, and a washer, 4^a, secured to the sleeve by the eyelet.

The upper end of the cord may be tied around the eyelet between the washer and the sleeve, or it may be merely moved 35 around the eyelet a sufficient number of times to frictionally hold it against accidental release.

40 The lower end of the cord is adjustably connectible with an eyelet, 6, and a friction washer, 7, bound thereby to the sleeve.

In using the device, the lower end of the cord is passed part-way around the eyelet, 6, between the washer, 7, and the sleeve, and drawn upwardly until the sleeve has been 45 gathered or shirred between the two eyelets, 4 and 6, to shorten the sleeve to the desired length.

50 The end of the cord is then wound around the eyelet, 6, a sufficient number of times to frictionally secure it against accidental release.

The lower end of the cord may be released by unwinding it from the eyelet, 6.

55 In Figures 2^a and 2^b, the preferred embodiment of my invention is illustrated. The sleeve or article to which the invention is applied is provided with an eyelet 4 in

the form of a tubular rivet to constitute one of a pair of openings, and a disk 4^a is mounted upon the tubular rivet between one 60 of its flanges and the article. The other opening 3^b of the pair is formed directly in the article or sleeve adjacent the eyelet 4 for a purpose which will be presently described.

At a point spaced a considerable distance 65 from the pair of openings 3^b and 4^b, a second eyelet 6 is provided in the article, in the form of a tubular rivet, as shown, and a washer 7 of disk shape is mounted upon this rivet between a flange of the rivet and the 70 article to form a frictional cord holder.

A strand of flexible material in the form of a cord 3^a has one end secured to the rivet 6. The opposite end of this strand of cord is threaded first through the opening 3^b to 75 pass within the sleeve or article and then is passed through the tubular rivet 4 to the exterior side of the article or sleeve from where it is directed back toward the rivet 6 and wrapped about the friction washer 7 80 where it is detachably secured. By pulling upon the free end of the cord it will be seen that the sleeve may be shirred as illustrated in Figures 2^a and 2^b, or in other words, the eyelets 4 and 6 may be drawn 85 closer together so as to provide for a very effective adjustable fastener which may be employed advantageously as any kind of closure fastener.

The eyelets used as fastening devices may 90 be either metal eyelets as represented at 4, in Fig. 2, or eyelets formed by buttonholes stitching as shown at 6, in Fig. 2.

I do not wish to be limited to the constructions shown and above described, as, for certain purposes of the invention, various changes may be made in the form and arrangement of various parts of the device without departing from the spirit of the invention.

95 What I claim as new and desire to secure by Letters Patent is—

The combination with an article having a pair of openings, a fastener secured to said article in spaced relation to said openings, 100 a friction disk mounted upon said fastener, a cord having one end fixed to said fastener, said cord being threaded through said pair of openings and having its other end releasably secured to said friction disk.

105 In testimony whereof, I have hereunto set my hand this 11th day of September, 1925.

CLARENCE R. MARTINEAU.
